(57) **CLAIM**

The ornamental design for a dino skull pendant, as shown and described.

DESCRIPTION

FIG. 1 is a front perspective view of a dino skull pendant in accordance with my design;

FIG. 2 is a rear perspective view of the design of FIG. 1; FIG. 3 is a front elevational view of the design of FIG. 1; FIG. 4 is a rear elevational view of the design of FIG. 1; FIG. 5 is a right side elevational view of the design of FIG. 1;

FIG. 6 is a left side elevational view of the design of FIG. 1; FIG. 7 is top plan view of the design of FIG. 1; and, FIG. 8 is a bottom plan view of the design of FIG. 1. The broken lines illustrate portions of the dino skull pendant which form no part of the claimed design.

1 Claim, 6 Drawing Sheets
